BUTTER CURLER

William R. Galter, Chicago, Ill.

Application January 3, 1950, Serial No. 6,979

Term of patent 3½ years

(Cl. D44—29)

To all whom it may concern:

Be it known that I, William R. Galter, a citizen of the United States of America, residing at 159 East Ohio Street, Chicago, Illinois, have invented a new, original, and ornamental Design for Butter Curler, of which the following is a specification, reference being made to the accompanying drawing, forming part hereof.

Referring to the drawing, Fig. 1 is a top plan view of a butter curler embodying my new design; Fig. 2 is a bottom plan view; Fig. 3 is a side elevational view and Fig. 4 is a front end elevational view of my butter curler.

I claim:

The ornamental design for a butter curler, substantially as shown.

WILLIAM R. GALTER.
